UNITED STATES PATENT OFFICE.

JOHN HAUGLAND, OF CLINTON, HOUSTON, TEXAS.

FOLDING BED.

Application filed July 2, 1922. Serial No. 572,627.

To all whom it may concern:

Be it known that I, JOHN HAUGLAND, a citizen of the United States, residing at Clinton addition to the city of Houston, 5 Harris County, Texas, have invented a certain new and useful Improvement in Folding Beds, of which the following is a full, clear, and exact description, such as will enable others skilled in the art to which 10 it appertains to make and use the same.

My invention relates to beds, and has for its object the construction of a bed which may be stood up out of the way when not in use.

15 Another object is to provide a bed which may be tilted up at an angle so that the bed clothing may be properly aired and so that it may be possible to clean under the bed.

20 Another object is to provide means of easily moving the bed from one part of the room to another.

Other objects and advantages of my invention will be clear to one skilled in the 25 art from the description which follows.

Referring to the drawing herewith forming a part of this specification and wherein like numerals of reference are applied to like parts in all the views, Fig. 1 is a side 30 elevation of a bed embodying my improvement; Fig. 2 is a similar view showing the same in a different position; Fig. 3 is also a side elevation showing the bed standing on end; Fig. 4 is an end elevation; Figs. 35 5 and 6 are also end elevations viewed from the opposite position; and Fig. 7 is a view similar to that shown in Fig. 3 showing a covering for the bed.

In the construction of my bed I form 40 the foot thereof with two short upright side posts 1, spaced apart and having a top connecting piece 2 and a lower connecting piece 3. The member 3 is of somewhat heavier construction than the other members which 45 are made as light in construction as possible. Between the two side posts 1 are connecting rods 4. These rods are also of light construction and serve the purpose of an attachment for the bed clothes, as will be later described. The legs 5 at the foot 50 of the bed are extensions of the side posts 1 and are hinged thereto at 6 so that they may be swung outwardly and upwardly against the side posts as shown in Fig. 2.

55 I may, if desired, provide a strap or other flexible connection 7 centrally of the frame

member 3 for the purpose of handling the bed when it is thrown in inoperative position.

The head portion of the bed is made of 60 slightly heavier construction and comprises two side posts 8 connected at their upper ends by a cross bar 9. The head posts 8 and the foot posts 1 are connected and spaced apart by the side pieces 10 in the usual manner, said side pieces being made of strong light material and furnishing a support for the springs and mattress in the usual manner. The head portion of the bed is supported upon rectangular legs or blocks 65 11. This leg is divided diagonally to form two portions, a forward and inner portion 12, and an outer portion 13. These two parts are hinged together at 14 so that the part 13 may be thrown forwardly on the 70 said hinge and be latched back out of the way by means of a latch 15 shown in Fig. 2. The inner face of the section 12 of the legs furnishes a support for a cross board which 75 may be upholstered as shown at 16 to provide a seat when the bed is set in erect position.

When the leg 11 is folded back in position as shown in Fig. 2 I contemplate moving the bed about the room upon the inclined or beveled surface thus formed. To do this I recess the portion 12 of the leg for a short distance and set in this recess a rotatable roller or caster 17. I mount the 80 said roller in such position that the outer circumference will project slightly outward from the inclined face of the portion 12 and thus provide a rolling support for the bed when it is tilted up at an angle as shown in Fig. 2. A cooperating recess 18 is formed 85 in the section 11 of the support into which the projecting portion of the roller 17 may fit when the leg is in extended position as shown in Figs. 1, 3 and 7.

In the operation of this bed it is contemplated that when in use the bed will be extended as shown in Fig. 1 with the legs at both ends in operative position. The mattress and springs will be placed thereon and the sheets, pillows and other bedclothes usually employed will be placed thereon. When, however, the bed is not in use, it is contemplated that it will be tipped on end either in erect position as shown in Fig. 3 or at an angle to the floor as shown in Fig. 2. When 90 in such position the mattress and bedclothes will be held in position by being tied or 95

100

105

110

otherwise secured to the bars 14 at the foot of the bed. This may be done by having rings on the said rods connected with the mattress and clothes or by tight cords connected with the mattress and the bedclothes to the said rods as shown in dotted lines in Figs. 2 and 3. The portion 11 of the forward leg of the bed will be folded back on the hinges as shown in Fig. 2 and latched in 10 that position. The foot of the bed will then be raised up so that the weight of the bed will be supported on the rollers 17. If the material of the bed has been properly weighted this may be easily done. If it is 15 found, however, that the foot of the bed is not easily raised, I contemplate weighting the head portion of the bed so as to overbalance this portion and thus raise the foot portion more easily. This may be done by 20 placing a slab of lead or other material between two cross pieces 19 connecting the head post 8. There will thus be a central slab of lead 20 with boards on front and rear sides thereof between the spaced side 25 posts. It will be thus noted that the heavier weight will fall to one side of the forward leg 12 and thus assist in tipping the bed into erect position.

When the bed is in position shown in Fig. 30 it may be moved about the room with ease by engaging the strap 7 and balancing the same upon the rollers 12. The legs 5 at the foot of the bed may be doubled back on the hinge 6 as shown in Fig. 2 and the bedclothes will be thus exposed to the air or 35 sunlight as desired and it will be possible to clean beneath the bed with ease. When it is desired to place the bed out of the way it may be rolled up against the wall and forced 40 still further up into erect position as shown in Figs. 3 and 7. The portion 13 of the lower leg will then be unlatched and moved into operative position and will thus assist in supporting the bed in erect position. On 45 the lower side of the springs there may be a facing of strong canvas or leather formed to cooperate with the seat 16 and will thus form a lounge or settee. I contemplate that

one may form a drapery over the sides of the bed portion as shown at 20 in Fig. 7, if so 50 desired. This however, is optional and constitutes no portion of my invention.

The advantages of this construction will be obvious to one skilled in the art without further description. 55

What I claim as new and desire to protect by Letters Patent is:

1. A bed having one end thereof weighted, the supporting legs on the weighted end being divided diagonally and the parts hinged 60 together so that the outer half thereof may be folded back on said hinges, a roller on the inclined face of the inner half of each of said legs whereby the bed may be tipped up on to said rollers and moved about in the 65 manner described.

2. A bed having one end heavier than the other end, supporting legs on said heavy end of rectangular shape and divided diagonally so that the outer half thereof may be 70 swung out of the way and anti-friction means on the inclined portions of said legs when thus divided, whereby the bed may be tilted up on to said means and moved about as described. 75

3. A bed having a head and a foot portion, one end being weighted, supporting legs at each end, legs on the weighted end being divided diagonally and hinged to be folded back so as to support the bed on said 80 diagonally divided portion, and rollers on said divided legs which are presented to the floor when said bed is thus supported.

4. A bed having head and foot portions, supporting legs at each end, those on one 85 end being divided so that one part will fold back at an angle to the floor and the legs then support the bed in an inclined position, and rollers on said legs, which are brought into operative position when the bed is inclined, whereby said bed may be easily 90 moved.

In testimony whereof, I hereunto affix my signature, this the 29 day of June, A. D. 1922.

JOHN HAUGLAND.
